WILLIAM WEDDINGTON, OF ALEXANDRIA, INDIANA.

Letters Patent No. 70,053, dated October 22, 1867.

IMPROVED SAFETY-STIRRUP.

The Schedule referred to in these Letters Patent and making part of the same.

TO ALL WHOM IT MAY CONCERN:

Be it known that I, WILLIAM WEDDINGTON, of Alexandria, in the county of Madison, and State of Indiana, have invented a new and improved Safety-Stirrup; and I do hereby declare that the following is a full, clear, and exact description thereof, which will enable those skilled in the art to make and use the same, reference being had to the accompanying drawings, forming part of this specification, in which—

Figure 1 is a perspective view of my improved safety-stirrup.

Figure 2 is a central vertical section, taken in the line $z z$, fig. 1.

Figure 3 is a similar view, showing the foot-bar tilted up.

Similar letters of reference indicate corresponding parts.

This invention relates to a new and useful improvement in the construction of a saddle-stirrup, and consists in attaching a foot-piece or support to an ordinary stirrup, with pivots, in such a manner that the weight of the foot on the heel of the foot-piece shall tip it up or raise it between the bows of the stirrup, and thus release the foot in case of accident by the throwing of the rider, as hereinafter more particularly described.

In the drawing, A A are the side-bars, and B the foot-bar of an ordinary stirrup. C represents an extra foot-bar, made of iron or wood, which is hung on pivots $\alpha \alpha$ in the lower ends of the side bows A A in such a manner that it shall rest upon and be supported by the foot-bar B when in its proper position for holding the foot in the stirrup, as shown in fig. 1, while it can turn upon its pivots $\alpha \alpha$ and swing back between the bows A A, when the weight of the foot bears upon the heel or rear side of the bar C, as shown in fig. 3, thus releasing the foot from the stirrup readily in case of accident. The foot-bar C is turned up in front and bent backward, forming a triangular stirrup with a third bow, A', the upper end of which joins and bears against the head of the stirrup, when the foot-bar is in place for supporting the foot. The third bow A' receives and bears against the toe when the foot is introduced into the stirrup, thus preventing it from entering too far. The foot-bar C will rise in front by the pressure of the foot upon it behind the pivots $\alpha \alpha$, and thus throw out the foot and release it from the stirrup when a rider is thrown from his horse, and thus prevent the danger of being dragged by the foot hanging in the stirrup, which with the ordinary stirrup often happens and causes fatal accidents.

Having described my invention, I claim as new, and desire to secure by Letters Patent—

The foot-bar C pivoted at α in the ends of the bows A, and resting upon the projecting foot-bar B, and provided with a bow, A', whose upper curved end presses against the head of the stirrup when the foot is placed therein, as herein set forth for the purpose specified.

WM. WEDDINGTON.
